UNITED STATES PATENT OFFICE.

RALPH G. BENSON, OF CHICAGO, ILLINOIS, ASSIGNOR TO THE CABLE COMPANY, OF CHICAGO, ILLINOIS, A CORPORATION OF ILLINOIS.

PNEUMATIC ACTION FOR MUSICAL INSTRUMENTS.

1,235,759.

Specification of Letters Patent.

Patented Aug. 7, 1917.

Application filed July 20, 1910, Serial No. 572,985. Renewed April 4, 1917. Serial No. 159,740.

To all whom it may concern:

Be it known that I, RALPH G. BENSON, a citizen of the United States of America, residing at Chicago, in the county of Cook and 5 State of Illinois, have invented new and useful Improvements in Pneumatic Actions for Musical Instruments, of which the following is a specification.

This invention relates to musical instruments which may be mechanically actuated and automatically or otherwise controlled in actuation and it especially concerns the construction, arrangement and connection of an action to be used therefor, the principal 10 objects being to provide a compactly arranged structure wherein the parts are so disposed and detachably secured in position as to facilitate access thereto and detachment or removal thereof and to embody the more 15 delicate parts in detachable units to facilitate exchange or transposition thereof.

Figure 1 is a front view of the upper portion of a pneumatically-actuated piano, parts of the case being broken away to disclose the 20 arrangement above the key-bed of a pneumatic action constructed in accordance with my invention.

Fig. 2 is an enlarged vertical sectional view, upon the line 2—2 of Fig. 1, of the 25 pneumatic action, the usual piano note-sounding action and associated parts.

Fig. 3 is a fragmentary front view of my improved pneumatic action, illustrating the method preferably employed in detachably 30 securing and clamping the principal divisions in position.

Fig. 4 is a vertical sectional view, upon the line 4—4 of Fig. 3, of a hollow support or "header," illustrating the method preferably 35 employed in detachably securing the principal divisions in position thereupon and of detachably securing the support in position to permit pneumatic communication of each division with a wind-inducing apparatus.

Fig. 5 is a sectional view, upon the line 45 5—5 of Fig. 3, of a tie or clamp which I employ in connection with the principal divisions in obtaining rigidity.

Fig. 6 is an enlarged plan of an individual "power" pneumatic and the controlling valve-action associated therewith, showing the 50 separate constituent units in correct position.

Fig. 7 is a vertical sectional view, upon the line 7—7 of Fig. 6.

Figs. 8 and 9 are detail views of parts to be hereinafter described.

Fig. 10 is a detail view of a portion of the action mechanism.

A, B and C indicate removable parts of the piano case. D indicates the key-bed, E, the keys, F, the strings, G, the hammers and H, the piano action-supporting frame. All of these parts are well-known and are not included in my invention.

I prefer to place the pneumatic action above keys E and immediately in front of the piano-action-stickers 1 (Fig. 2) and to support and connect it in a manner that will 70 not interfere with manual playing of the instrument.

The usual means may be employed for automatically controlling the operation of the pneumatic action, comprising a traveling 75 perforated music-sheet 2 and a tracker-board 3 across which the music-sheet is propelled in any desired manner to accomplish alternate opening and closing of selected tracker-apertures which constitute inlets for the 80 well-known tracker-tubes 4.

Stickers 1 may be arranged in the usual or any desired manner for reciprocal movement through manipulation of keys E to cause operation of hammers G. Levers 5 are pivoted at their rear ends to flanges 6 which are secured to a bar 7 firmly held in place upon the frame H of the piano action. Each lever extends through a slot in the upper end of one of the stickers 1 beneath a pin 8. The 90 slots are long enough to permit full upward movement of stickers 1 by manipulation of keys E without disturbance of levers 5 and upward movement of the forward end of said levers may cause movement of stickers 95 1 without disturbance of keys E by upwardly bearing upon the under sides of pins 8. Upward movement of the forward end of levers 5 may be adjustably limited by a stop-rail 9 preferably secured to the frame H and 100 having separate adjusting means for the individual levers. The inoperative position of levers 5 is determined by an adjustment which will be hereinafter described.

I prefer to place the wind-inducing apparatus, which may be of any preferred construction, below key-bed D and adjacent to piano-strings F. I have indicated by 105 10 10

(Figs. 1 and 2) portions of an apparatus of this character communicating through conduits 11 11 with passages 12 12 which are cut through the key-bed near either end of 5 the instrument. (Fig. 1.)

Opposite ends of the pneumatic action are similarly supported and secured and a description of the construction at one end thereof will suffice. Post 13 is hollow and is 10 secured in air-tight connection with passage 12 by means of bolt 14, anchor-block 15 and plate 16. Block 15 is firmly secured upon the upper side of the key-bed and is apertured to provide pneumatic communication 15 between passage 12 and post 13. Plate 16 is secured within the aperture in the block and is so positioned, perforated, or otherwise arranged as not to interfere with free wind passage. Bolt 14 is passed end- 20 wise through the post into threaded engagement with plate 16. Post 13 may thus be placed upon block 15 and clamped in position and air-tight connection through tightening of the bolt or the bolt may be 25 unscrewed from the plate and the post removed together with any attachments thereto.

Hollow rectangular bars 17 17 extend completely across the piano over the keys and 30 are individually secured near each end upon the front side of a post 13 by means of plates 18 18 and screws 19 19. The contacting sides of the bars and posts are respectively provided with registering apertures 35 20 and 21, so that the interior of each bar 17, when secured in position, becomes an individual wind-chamber or passage in which the pneumatic pressure may be varied by the wind-inducing apparatus 10 through posts 40 13 13, passages 12 12 and conduits 11 11.

I obtain a rigid frame-work by providing the front sides of the posts with transverse channels or recesses 17, each for the reception of the intersecting portion of the rear 45 side of a bar, and provide against twisting of the bars by means of clamps or ties which may be arranged at convenient locations between the posts. (Figs. 1, 3 and 5.) I have shown a clamp consisting of two plates 22 50 and 23, which may extend across and be drawn firmly down upon the opposite sides of the several bars by means of screws 24. One plate may be grooved or recessed upon its inner side to embrace that portion of the 55 sides of the several bars across which it extends and thus prevent displacement of the clamp through vibration.

Individual primary casings 25 and individual secondary casings 26 are arranged respectively at the front and rear of bars 17 and are screwed or otherwise removably secured thereupon. (Figs. 2, 3, 6 and 7.) Each primary casing 25 is provided with an aperture 27 and each secondary casing 26 is 65 provided with an aperture 28. (Fig. 7.)

When the individual primary casings are secured in position each aperture 27 therein registers with one of a number of apertures 29 in the front faces of bars 17 and when the individual secondary casings are secured 70 in position each aperture 28 therein registers with one of a number of apertures 30 in the rear faces of said bars.

Each primary casing 25 is provided at its opposite inner edges with annular recesses 75 31 and 32 and comprises two concentric chambers 33 and 34 which are separated by a partition 35 centrally apertured at 36. Chamber 33 is inclosed by outer wall 37 which is in the form of a plate fitted tightly 80 within annular recess 31 and centrally apertured at 38. Chamber 33 is also provided with an aperture 39 which is fitted with a tube 40. Aperture 27 opens into chamber 34. Each primary valve comprises a stem 41, 85 an inner disk 42 and an outer disk 43. The valve-stem is passed through apertures 36 and 38 and the valve-disks are supported by the stem near the opposite outer surfaces of partition 35 and wall 37 and provided upon their adjacent faces with leather or other suitable packing material. Apertures 36 and 38 are of greater diameter than the valve-stem so that, in addition to guiding the valve, they may serve as ports to be 95 alternately covered by valve-disks 42 and 43. Reciprocal movement of the primary valve will cause alternate communication of chamber 33 and tube 40 with the atmosphere through aperture 38 and with chamber 34 100 through aperture 36.

Each secondary casing 26 is provided at its opposite inner edges with annular recesses 44 and 45 and comprises two concentric chambers 46 and 47 which are separated 105 by a partition 48 provided with a central port 49. The edge of the casing is internally threaded about recess 44 and chamber 46 is inclosed by outer wall 50 which is in the form of a plate having a central port 52. 110 The plate is threaded about its outer edge and screwed within recess 44 upon packing-ring 51. Chamber 46 is provided with an aperture 70. Aperture 28 opens into chamber 47. Each secondary valve comprises a 115 stem 53 which carries an adjustable head 54 and a flexibly attached disk 55. The stem extends through ports 49 and 52 and is guided at its outer end by a guide 56 which is riveted or otherwise secured upon the outside of wall 50. Stem 53 is threaded at its inner end to provide adjustment for the head 54. For alternately closing ports 49 and 52, I prefer to employ the opposite surfaces of the single valve-disk 55, which I 125 provide with leather or other suitable packing material.

The edge of primary casing 25 is internally threaded about recess 32 and chamber 34 is closed by a flexible diaphragm 57. The 130

edge of secondary casing 26 is internally threaded about recess 45 and chamber 47 is also closed by a diaphragm 57. Diaphragms 57 for all of the casings are alike in construction and similarly held in position. Each is composed of a circular piece of reasonably impervious membrane, such as thin leather or rubber-coated silk, and is preferably secured to a packing-ring 58 and provided upon one surface, at or about its central part, with a disk of cardboard or other stiff material 58^a. (Fig. 8.) Each diaphragm-and-ring combination is of such diameter that it may nicely fit within one of the recesses 32 or 45 and be clamped against the shoulder thereof to seal the respective chamber 34 or 47 and position its card-board disk close to, and directly in alinement with, the respective valve-stem 41 or 53. Each cup 60 is shaped to permit tubular connection therewith and to fit within one of the recesses 32 or 45 against packing-ring 58 and each screw-ring 59 is threaded about its outer edge so that it may be screwed within one of these recesses against the border of a cup 60 and thereby clamp cup, packing-ring and diaphragm firmly within the recess and against the shoulder thereof. With the just-described parts in position, a chamber is formed between each diaphragm and cup. Secondary diaphragm-chamber 61 communicates through tube 40 with primary valve-chamber 33 and primary diaphragm-chamber 62 communicates through tube 63 and one of a series of passages 66 in the wall of a vent-chamber 64 (Fig. 4) with one of the tracker-tubes 4. Vent-chamber 64 communicates through tube 65 with one or both of the hollow posts 13 and is in this manner provided with the same variations in pneumatic pressure as are other parts of the action. Each passage 66 communicates with chamber 64 through a pin-hole or vent 67.

Chamber 46 of each secondary casing 26 is connected with a "power" pneumatic 68 through apertures 70 and 71 by means of passage-way 69. Movable side 72 of each pneumatic is provided with a lug 73 and the lugs of the two lower rows or tiers of pneumatics are fitted with pivotally-attached upwardly-turned pitman-rods 73^a which pass through a guide 74 preferably secured to and removable with the pneumatic action. (Fig. 2.) Pitman-rods 73^a are provided with buttons or heads 73^b at their upper ends and the upper surfaces of these heads are arranged to project to a level with the upper surfaces of the lugs of the upper row or tier of pneumatics. When the action is in correct position, the forward end of each of the levers 5 projects over and slightly above a corresponding pitman-head 73^b or pneumatic-lug 73 and each lever carries an adjusting device 75 arranged to contact with

the particular head or lug over which the lever is positioned.

This pneumatic action is arranged to be operated by suction or air-pressure less than atmospheric pressure but slight modifications may be made by those skilled in the art, without departing from the spirit or scope of my invention, by which the action may be arranged for operation by air-pressure greater than atmospheric pressure. 75

Operation of the wind-inducing apparatus 10 will reduce the air-pressure in all of the chambers 34 and 47 through apertures 27, 29, 28 and 30, hollow bars 17, apertures 20 and 21, hollow posts 13, passages 12 and conduits 11. Air-pressure is likewise reduced in the vent-chamber 64 through tube 65 and, when all of the apertures in the tracker 3 are sealed by an imperforate part of the music-sheet 2, the same reduction in air pressure will take place in each of the tracker-tubes 4, tubes 63 and primary diaphragm-chambers 62, by means of the individual vents 67 in chamber 64. Under such conditions, the diaphragm 57 of each primary casing 25 will rest between two approximately equal degrees of reduced air pressure; atmospheric pressure will cause the respective primary valves to retain their innermost position, holding the outer disk 43 of each valve 90 closed over the respective aperture 38, and the air-pressure within each secondary diaphragm-chamber 61, tube 40 and primary valve-chamber 33 will be reduced to a similar degree through uncovered aperture 36; the 100 diaphragm 57 of each secondary casing 26 will therefore rest between two approximately equal degrees of reduced air-pressure and atmospheric pressure will cause the respective secondary valve to retain its innermost position, holding the port 49 closed between chambers 46 and 47 and holding port 52 open to admit atmospheric pressure to "power" pneumatic 68 through apertures 70 and 71 and passage-way 69. When a 110 tracker-aperture is uncovered by a perforation in the music-sheet, atmospheric pressure will be admitted to the corresponding tracker-tube 4, passage 66, tube 63 and primary diaphragm-chamber 62, the respective 115 vent 67 being too small to withdraw the air as fast as it is admitted through the open tracker-aperture. The equilibrium of primary-diaphragm 57 is instantly destroyed by this change of air-pressure in chamber 62 120 and it is forced inwardly to move the primary valve outwardly, thereby interrupting communication between chambers 33 and 34 and establishing communication between chamber 33 and the atmosphere. The consequent admission of atmospheric pressure through aperture 38 to chamber 33, tube 40 and secondary diaphragm-chamber 61 destroys the equilibrium of secondary-diaphragm 57 and it is also forced inwardly to 130

move the secondary valve outwardly, thereby interrupting communication of "power" pneumatic 68, passage 69 and chamber 46 with the atmosphere and establishing communication of these parts with chamber 47. A normal restoration of all the parts is occasioned by re-sealing the respective tracker-aperture by an imperforate portion of the music-sheet 5. The collapse and recovery of 10 the "power" pneumatic are thus alternately accomplished through the opening and closing of the controlling tracker-aperture.

I claim and desire to secure by Letters Patent:

- 15 1. In a pneumatic action for a musical instrument, a pneumatic action frame comprising a first hollow member provided with a groove, a second hollow member having an end and a side and supporting said devices, the interiors of the first and second members communicating with each other, and means 20 adjustable externally of the second member for detachably securing a portion of the side thereof within the groove in the first member of said frame.
- 20 2. In a pneumatic action for a musical instrument, a pneumatic action frame, a hollow post provided with a groove, a hollow bar having an end and a side for supporting 25 action devices, the interiors of said post and said bar communicating with each other, and means adjustable externally of said bar for detachably securing a portion of the side thereof within the groove in said post.
- 30 3. In a pneumatic action for a musical instrument, a pneumatic action frame comprising a first hollow member provided with a groove and an aperture, the aperture being located in the wall of the member at the bottom of the groove, a second hollow member 35 having an end and a side and an aperture in the side for supporting pneumatic action devices, and means adjustable externally of the second member for detachably securing 40 a portion of the side thereof within the groove in the first member of said frame to permit registration of the aperture in the side of the second member with the aperture in the wall of the first member of said frame.
- 40 4. In a pneumatic action for a musical instrument, a pneumatic action frame comprising a hollow post provided with a groove and an aperture, the aperture being located in the wall of said post at the bottom of the groove, a hollow bar having an end and 45 a side and an aperture in the side and supporting pneumatic action devices, and means adjustable externally of said bar for detachably securing a portion of the side thereof within the groove in said post to permit registration of the aperture in the side of said bar with the aperture in the wall of said post.
- 50 5. In a pneumatic action for a musical instrument, the combination with a hollow

post, a hollow bar for supporting individual action devices, of means detachably securing said bar to said post with the interiors of said bar and said post in communication with each other and means detachably securing 70 said action devices individually upon and entirely without said bar with the interiors of said devices and said bar in communication with each other.

6. In a pneumatic action for a musical instrument, an air-chamber provided with apertures in the opposite sides thereof, individual valve-casings located on opposite sides of said air-chamber and provided with apertures in the walls thereof which register 80 with the apertures in the sides of said air-chamber, a conduit connected with one of said valve-casings and a second conduit connecting two of said valve-casings.

7. In a pneumatic action for a musical instrument, a frame, a tubular air-chamber associated with said frame, individual valve-casings separately and, detachably secured upon opposite sides of said air-chamber, the interiors of said air-chamber and said valve-casings communicating with each other, a conduit connected with one of said valve-casings and a second conduit connecting two of said valve-casings.

8. In a pneumatic action for a musical instrument, an air-chamber provided with apertures in the opposite sides thereof, individual casings located on opposite sides of said air-chamber and provided with apertures in the walls thereof which register 100 with the apertures in the sides of said air-chamber, a valve and a valve-operating device embodied in each of said casings, and a conduit connecting two of said casings.

9. In a pneumatic action for a musical instrument, an air-chamber, individual casings located on opposite sides of said air-chamber, the interiors of said air-chamber and said casings communicating with each other, valves in said casings, and a conduit 105 extending from one only of said casings on one side of said air-chamber to one only of said casings on the opposite thereof, whereby the valve in the casing on one side of said air-chamber may be actuated through 110 actuation of the valve in the conduit-connected casing on the opposite side thereof.

10. In a pneumatic action for a musical instrument, a frame, a tubular air-chamber comprised in said frame, individual primary 120 and secondary valve-casings separately supported on opposite sides of said air-chamber, the interiors of said air-chamber and said valve-casings communicating with each other, and a conduit connecting said valve- 125 casings.

11. In a pneumatic action for a musical instrument, a frame, a tubular air-chamber comprised in said frame, an individually-removable casing supported as a unit wholly 130

outside of and upon said air-chamber, the interiors of said air-chamber and said casing communicating with each other, a valve and a valve-operating pneumatic 5 within said casing, and a power-pneumatic located outside of said air-chamber, within said frame and communicating with said casing; said casing, valve and valve-operating pneumatic being associated with said 10 power-pneumatic to effect control thereof in operation but otherwise separate therefrom as a complete unit.

12. In a pneumatic action for a musical instrument, a frame, a tubular air-chamber 15 comprised in said frame, an individual casing supported as a unit wholly outside of and upon said air-chamber, the interiors of said air-chamber and said casing communicating with each other, a valve and a valve-operating pneumatic within said casing, and a power-pneumatic removably positioned within said frame beneath said air-chamber and said casing; said power-pneumatic being detachably secured in communication with said casing and thus associated 20 with said valve and said valve-operating pneumatic for control thereby in operation but otherwise separate therefrom as an individual unit.

13. In a pneumatic action for a musical instrument, an air-chamber provided with an aperture in the wall thereof, an individually-removable casing provided with an aperture in the wall thereof and an annular 35 recess (32), a wall provided with a valve-port, a valve, a valve-operating device, and means for removably securing said casing in position upon said air-chamber and the aperture in the wall of said casing in air-tight registration with the aperture in the wall of said air-chamber to permit detachment and removal of said casing with the parts therein contained without disturbance of other parts; said wall, valve and valve-operating 40 device being contained within said casing and said valve-operating device being releasably clamped in the recess in said casing.

14. In a pneumatic action for a musical instrument, an individual casing, a single 50 body-part comprised in said casing, an apertured partition in said body-part forming two concentric chambers therein, said body-part being provided with an aperture in the wall thereof opening into each of the 55 chambers thus formed and with an annular recess about its edge, an outer wall fitted within the recess in said body-part, a valve and a valve-operating pneumatic in said body-part; said valve acting to close the 60 aperture in said partition.

15. In a pneumatic action for a musical instrument, an individual casing, a single 55 body-part comprised in said casing, an apertured partition in said body-part forming two concentric chambers therein, said body-

part being provided with an aperture in the wall thereof opening into each of the chambers thus formed and with an annular screw-threaded recess about its edge, an outer screw-threaded wall screwed into the recess 70 in said body-part, a valve and a valve-operating pneumatic in said body-part; said valve acting to close the aperture in said partition.

16. In a pneumatic action for a musical 75 instrument, an individual casing, a single screw-threaded body-part comprised in said casing, a valve in said body-part, a valve-operating pneumatic, an outer removable wall, an externally screw-threaded ring 80 screwed into said body-part and holding said wall and said pneumatic in position in said body-part, said wall and said pneumatic forming a chamber in said body-part when held in position therein by said ring, and a 85 conduit communicating with the chamber thus formed.

17. In a pneumatic action for a musical instrument, an individual valve-easing, a single body-part comprised in said valve-easing, 90 an outer wall secured in said body-part and provided with a valve-port, a flexible diaphragm releasably clamped in said body-part, and an apertured partition in said body-part between said wall and said diaphragm; said partition and said diaphragm forming a middle and two outer chambers within said body-part and said valve-easing having ports opening into each 95 of the chambers so formed.

18. In a pneumatic action for a musical instrument, an individual casing, a single body-part comprised in said casing, a valve in said body-part, two outer removable walls and a flexible diaphragm secured in said 105 body-part, and an apertured partition in said body-part between one of said walls and said diaphragm; said partition and said diaphragm forming a middle and two outer chambers within said body-part, said casing 110 having ports opening into each of the chambers so formed, and said diaphragm acting upon said valve to control chamber-communication through the aperture in said partition.

19. In a pneumatic action for a musical instrument, a hollow bar and action-valve devices mounted upon said bar; the interior of said bar being unobstructed by projecting or connecting parts associated with said devices.

20. The combination of a wind chamber, a valve casing located at one side of said wind chamber, and means for holding said valve casing in position; said means comprising securing devices extending over and under the wind chamber.

21. The combination of a wind chamber, a valve casing located at one side of said wind chamber, and means for securing both

- top and bottom of said valve casing to said wind chamber.
22. The combination of a wind chamber, valve casings on opposite sides of said wind chamber, and means for holding said valve casings in position, said means extending between said valve casings above said wind chamber. 70
23. The combination with a wind chamber, 10 of valve casings on opposite sides of said wind chamber, and means for holding said valve casings in position, said means extending between said valve casings below said wind chamber. 75
- 15 24. The combination with a wind chamber, of valve casings on opposite sides of said wind chamber, and means for holding said valve casings in position, said means extending between said valve casings above 20 and below said wind chamber. 80
25. The combination of a wind chamber, a valve casing located at one side of said wind chamber, and screws for holding said valve casing in position, said screws engaging the 25 top and bottom of the valve casing above and below the wind chamber. 85
- 30 26. The combination of a wind chamber, valve casings located on opposite sides of said wind chamber and screws for holding 30 said valve casings in position, said screws engaging the tops and bottoms of the valve casings above and below the wind chamber, said valve casings being provided with upwardly and downwardly projecting lugs 35 through which said screws pass and the top and bottom of said wind chamber being provided with longitudinally extending strips secured to the wind chamber, said screws engaging said strips. 90
- 40 27. The combination of a wind chamber, a valve casing located at one side of said wind chamber, a power pneumatic located below said valve casing and said wind chamber, and means for supporting said power pneumatic, said means being located at one side 45 of said valve casing. 95
- 50 28. The combination of a wind chamber, a valve casing located at one side of said wind chamber, a power pneumatic located below said valve casing, and means for supporting said power pneumatic, said means being in turn supported by said valve casing. 100
- 55 29. The combination of a wind chamber, a valve casing at one side of said wind chamber, a power pneumatic below said valve casing, and means for supporting said power pneumatic, said means comprising a tubular member attached to said valve casing and forming a windway between the same and 60 said pneumatic, said tubular member extending downwardly alongside of the valve casing and being secured at its lower end to said pneumatic. 105
- 65 30. The combination with a wind chamber, of valve casings located on opposite sides of 110
- said wind chamber, a power pneumatic located below the wind chamber and said valve casings, and tubular connections extending between the valve casings and located between the latter and said power pneumatic. 70
31. The combination of a wind chamber, a valve casing on one side thereof, a power pneumatic located below said valve casing, a tubular connection extending downwardly at one side of said valve casing and serving 75 as a windway between said valve casing and said pneumatic and also as a support for the latter, and means for securing said tubular connection detachably to said valve casing. 80
32. The combination of a wind chamber, a valve casing on one side thereof, a power pneumatic located below said valve casing, a tubular connection extending downwardly at one side of said valve casing and serving 85 as a windway between said valve casing and said pneumatic and also as a support for the latter, and means for connecting said tubular connection detachably to the valve casing and also to the pneumatic. 85
33. The combination of a wind chamber, a valve casing mounted at one side of said wind chamber, a power pneumatic located below said wind chamber, and means for supporting said power pneumatic detachably 90
- 95 in position. 95
34. The combination of a wind chamber, a valve casing detachably mounted at one side thereof, a power pneumatic below the valve casing and a support for the pneumatic detachably connected with the pneumatic and wind chamber. 100
35. The combination of a wind chamber, valve casings on opposite sides of the wind chamber, means for holding the valve casings in position, said means extending between the valve casings above and below the wind chamber and a pneumatic supported below the wind chamber and valve casings. 105
36. The combination of a wind chamber, valve casings on opposite sides of said wind chamber, means for detachably securing the valve casings in position, said means extending above and below the wind chamber, a pneumatic below the wind chamber, and means for detachably supporting said pneumatic. 110
- 115
37. The combination of a wind chamber, a valve casing located at one side of said wind chamber, said valve casing being of substantially the same height as the wind chamber and having its top and bottom substantially level with the top and bottom of the wind chamber, and means for holding said valve casing in position, said means being located above the wind trunk and valve casing. 120
- 125
38. The combination of a wind chamber, a valve casing located at one side of said wind chamber, said valve casing being of 130

substantially the same height as the wind chamber and having its top and bottom substantially level with the top and bottom of the wind chamber, and means for holding 5 said valve casing in position, said means being located above the wind chamber and valve casing and also below the same.

39. The combination of a wind chamber and a valve casing located at one side of 10 the wind trunk, the top of the valve casing being substantially level with the top of the wind trunk, and means for holding said valve casing in position, said means being positioned above the wind chamber and valve 15 casing.

40. The combination with a wind chamber, of a valve casing mounted at one side of the wind chamber, said valve casing having its top substantially level with the top 20 of the wind chamber and means for securing said valve casing in position, said means being located above the wind chamber and valve casing, and comprising members projecting upwardly from the same and securing 25 ing devices engaging said members.

41. The combination of a wind trunk and a valve casing detachably secured in position at one side of the wind trunk, said valve casing being provided with a valve seat removable from the valve casing independent 30 of the connection of the casing and wind trunk.

42. The combination of a wind chamber and a valve casing detachably located at one 35 side of the wind chamber, said valve casing having a detachable top and a detachable bottom.

43. The combination of a wind chamber and a valve casing at one side of the wind 40 chamber, said valve casing comprising a single body part having a transverse apertured partition located between the top and bottom of said body part and also having side apertures above and below said partition, said single body part being provided with a removable top adapted to form a valve seat and a removable bottom adapted 45 to form a diaphragm support.

44. A valve casing comprising a single body 50 part provided with an integrally formed transverse apertured partition located between the top and bottom of said body part, said body part being provided with a bodily removable top having an aperture and constructed to form a valve seat and being also provided with a bodily removable bottom member constructed to form a diaphragm support.

45. A valve casing comprising a single body 55 part provided with an integrally formed transverse apertured partition located between the top and bottom of said body part,

said body part being provided with a bodily removable top having an aperture and constructed to form a valve seat and being also 60 provided with a bodily removable bottom member constructed to form a diaphragm support, said body part being constructed with side apertures, one located above and the other below said transverse partition. 65

46. The combination with a wind chamber, of a power pneumatic located below the wind chamber, and means outside of the wind chamber for supporting said pneumatic, said means engaging and being supported by the top of the wind chamber and 70 extending downwardly therefrom to the pneumatic. 75

47. The combination with a wind chamber, of a pneumatic located below the wind chamber, and means for supporting said pneumatic, said means engaging and extending crosswise of the wind chamber and thence downwardly to the pneumatic. 80

48. The combination of a wind chamber, 85 a pneumatic below the wind chamber and a support for the pneumatic resting upon the top of the wind chamber and extending down at one side thereof to the pneumatic.

49. The combination of a wind chamber, 90 a pneumatic below the wind chamber and a support for the pneumatic engaging the wind chamber and extending down at one side thereof to the pneumatic, said support being detachably secured in position and 95 being detachably connected to the pneumatic.

50. The combination of a wind chamber, 100 a pneumatic below the wind chamber, a support for the pneumatic having a surface substantially in contact with one of the walls of the wind chamber, and screws for detachably securing said support to said wall. 105

51. The combination of a wind chamber, 105 a pneumatic below the wind chamber, a support for the pneumatic having a surface substantially in contact with one of the walls of the wind chamber, and means for detachably securing said support to said wall. 110

52. The combination with the wind chamber, of a pneumatic below said chamber, and a support for said pneumatic, said support extending over the top of said chamber and thence downwardly to said pneumatic and 115 being detachably secured to said chamber near the opposite sides thereof.

Signed at Chicago, Illinois, this 16th day of July, 1910, in the presence of two subscribing witnesses.

RALPH G. BENSON.
